UNITED STATES PATENT OFFICE.

WILLIAM S. HADAWAY, JR., OF NEW ROCHELLE, NEW YORK, ASSIGNOR TO THE CUTLER-HAMMER MFG. CO., A CORPORATION OF WISCONSIN.

CARBURETER.

1,374,649.

Specification of Letters Patent. Patented Apr. 12, 1921.

Application filed October 23, 1913. Serial No. 796,761.

To all whom it may concern:
Be it known that I, WILLIAM S. HADAWAY, Jr., a citizen of the United States, and a resident of New Rochelle, in the county of Westchester and State of New York, have invented certain new and useful Improvements in Carbureters, of which the following is a specification, reference being had to the accompanying drawings, forming 10 a part thereof.

My invention relates to carbureters and devices of this general character which are utilized for mixing a combustible vapor with air for use as fuel in internal combustion engines.

One object of my invention is to provide, in a device of this character, means for vaporizing gasoline or other suitable liquid by heat with an expenditure of a very small 20 amount of energy without necessarily raising the temperature of the device itself, or of the body of liquid which it contains.

Another object of my invention is to provide a simple means which may be readily applied to carbureters of well known types, for rapidly vaporizing the fuel independently of the suction of the engine.

Another object of my invention is to provide a simple and effective means for vaporizing the fuel of a gasoline engine at starting.

Other objects and advantages of my invention will be set forth hereinafter.

Referring to the drawings,—

Figure 1 is a sectional elevation of a carbureter of the float type equipped with the vaporizer of my invention.

Fig. 2 is a partially sectional plan view of the gas outlet of the carbureter of Fig. 1 including a sectional view of the vaporizer on a larger scale.

Figs. 3 and 4 are detail views of the vaporizer also on a larger scale.

A carbureter of the wick type arranged 45 and constructed in accordance with my invention is shown in longitudinal section in Fig. 5 and in enlarged sectional detail in Fig. 6.

Like characters of reference designate 50 corresponding parts in all the figures.

Referring particularly to Figs. 1 to 4 inclusive of the drawing,—the carbureter shown is intended to be illustrative of any suitable device of this general character, and 55 comprises the usual float chamber 10, a float

valve 15 which is governed by a float 16, a spraying nozzle 20 which is governed by a needle valve 21, a primary air inlet 25, an auxiliary air inlet 30 having a puppet valve 31, and a gas outlet 35.

The float 16 is preferably U-shaped and need not extend into a pocket 40 of the float chamber, which is directly below the gas outlet. In the bottom wall of the outlet 35 is a slot 36 through which a wick 37 extends. 60 Directly above the slot 36, in the top wall of the outlet, is a tapped hole 38. The wick may be supported in any suitable manner in position to be influenced by the heat generated in an electric heater 45.

For example, the heater may comprise a sheath 46 having a screw threaded collar or bushing 48 near one end.

Within the sheath is located suitable resistance elements such as a slotted ribbon 49 and insulating strips 50. The sheath is sealed into the collar or bushing 48 which fits closely into the tapped hole 38, and the body of the sheath is preferably composed of a pair of sheet metal strips welded together at their edges. One of the strips of which the sheath is composed, extends outwardly into a terminal cap 51 and supports a pair of terminals 52.

The wick may be of any suitable form 85 and may be similar in structure to ordinary lamp wick. The wick in the arrangement illustrated, is tubular and is slipped onto the heating element so that its upper end is in close contact with the sheath of the 90 heater and its lower end extends into the liquid in the float chamber pocket 40. The lower end of the wick may be supported against lateral displacement if necessary in order to prevent the wick from interfering 95 with the float.

In the device above described, the electric heater may be very advantageously utilized for starting purposes, only a relatively small quantity of electric energy being necessary 100 to produce immediate results and the usual spraying nozzle being utilized after the motor is in operation. Instead of this arrangement, the electric heater may be utilized for vaporizing the fuel at starting and 105 the wick arranged to continue the vaporizing after the electric energy is disconnected.

An arrangement designed to operate in this way is shown in Figs. 5 and 6 to which reference may now be had. A plurality 110

of wicks 37^a dip into liquid fuel contained in a chamber 55 which is supplied by a pump 56 from a fuel supply tank 56^a. An outlet or overflow 57 keeps the liquid level 5 in the chamber substantially constant.

Air is fed through a primary air inlet 25 and thence to a mixing chamber 58 through which the wicks extend and where it is charged with fuel vapor.

10 Extending transversely of the chamber 58 are a plurality of electric heaters 59 which may each correspond to the heater 45 of Fig. 1 and are arranged to vaporize the fuel which is fed to the upper parts of the 15 wicks by a capillary action. The heaters may be relied upon to maintain and continue the vaporization of the fuel but it is particularly desirable to supply energy to the heater in starting the motor with which 20 the carburetor is associated.

In any event only a small quantity of electric energy is required to produce immediate results.

My invention is therefore particularly advantageous for use on automobiles or boats 25 where the available supply of electric energy is very limited. The heat is applied so directly to such a small body of liquid in the wick, that immediate vaporization results, 30 although a very small quantity of electric energy is converted into heat.

Another important advantage arises from the fact that carburetors of well known 35 types and in fact carburetors already in service may be inexpensively equipped with my electric vaporizer. Furthermore, carburetors of well known types, designed only for use with comparatively volatile fuels such as gasolene may readily be adapted, by employing the vaporizer of my invention, to 40 operate with liquid fuels such as kerosene or alcohol having very much higher boiling points.

The advantages of this arrangement will 45 be well understood by those skilled in this art, for example it is not only possible to adapt a carburetor of well known type to handle heavier fuels, but both the engine and the carburetor may be designed for the 50 lighter fuels and may successfully operate on heavier fuels by merely equipping the carburetor with the electric vaporizer of my invention.

The devices shown and described herein 55 are covered broadly by the claims of Patent No. 1,163,657, application for which was filed of even date herewith.

I do not intend to be limited by the term "carburetor" to a device for preparing fuel 60 only for use in internal combustion engines, but on the contrary, I refer to a vaporizer or mixer in a broader sense, which prepares fuel either for this purpose or for any other purpose, as for example, for supplying a 65 gas burner.

Various modifications and adaptations of my invention may be effected and I intend that only such limitations be imposed as are indicated in the appended claims.

What I claim is:

1. A carburetor comprising a mixing chamber, a liquid fuel containing chamber, a capillary agent for transferring fuel from the fuel chamber to the mixing chamber and a heater acting upon the capillary agent for 75 vaporizing the liquid in the chamber.

2. A carburetor comprising a fuel containing chamber, a mixing chamber, a spray nozzle discharging into the mixing chamber, a capillary agent for transferring fuel from the fuel chamber to the mixing chamber and a heater acting upon the capillary agent for vaporizing the liquid in the chamber.

3. A carburetor comprising a mixing chamber, a liquid fuel containing chamber, 25 a wick for transferring fuel from the fuel chamber to the mixing chamber and a heater acting upon the wick for vaporizing the liquid in the chamber.

4. A carburetor comprising a fuel containing chamber, a mixing chamber, a spray nozzle discharging into the mixing chamber, a wick for transferring fuel from the fuel chamber to the mixing chamber and a heater acting directly upon the wick for vaporizing the liquid in the chamber.

5. A carburetor comprising a mixing chamber, means arranged to transfer liquid fuel by capillary action to said chamber and means acting directly upon the first 100 named means for accelerating the vaporization of the fuel in the mixing chamber.

6. A carburetor comprising a mixing chamber, a wick arranged to transfer liquid fuel by capillary action to said chamber 105 and means acting directly upon the wick for accelerating the vaporization of the fuel in the mixing chamber.

7. A carburetor comprising a mixing chamber, a wick arranged to transfer liquid 110 fuel by capillary action to said chamber and a heater acting directly upon the wick for accelerating the vaporization of the fuel in the mixing chamber.

8. A carburetor comprising a mixing 115 chamber, a wick arranged to transfer liquid fuel by capillary action to said chamber and an electric heater acting directly upon the wick for accelerating the vaporization of the fuel in the mixing chamber.

9. A carburetor comprising a mixing chamber, a wick arranged to transfer liquid fuel by capillary action to said chamber, an air inlet for admitting air to the chamber and an electric heater adapted to act 120 directly upon the wick for initiating the vaporization of the fuel in the chamber.

10. A carburetor comprising a mixing chamber, an electric heater unit extending 125 into the chamber and a wick in contact with 130

said unit in the chamber and depending therefrom into a body of liquid.

11. A carburetor comprising a mixing chamber, an electric heater unit extending into the chamber and traversing the path of gases therethrough and a wick surrounding that part of the heater unit which is in the mixing chamber and depending therefrom into a body of liquid below the mixing chamber.

12. A carburetor comprising a mixing chamber, a flattened electric heater unit extending into the chamber and traversing the path of gases therethrough with its flattened sides parallel with the direction of flow of the gases and a wick surrounding that part of the heater unit which is in the mixing chamber and depending therefrom into a body of liquid below the mixing chamber.

13. A vaporizer comprising a wick one end of which is adapted to be immersed in a liquid fuel, the other end being out of the liquid and arranged in a passage so that the end within the passage draws the liquid fuel by capillary action whereby vaporization is accelerated.

14. In a vaporizer means for increasing the rate of evaporation by drawing a liquid fuel into a chamber by capillary action.

15. In the combination of liquid fuel and a chamber, means for accelerating evaporation of the fuel by capillary action.

16. In the combination of liquid fuel and a chamber, means for accelerating evaporation of the fuel by capillary action, said means including a wick having a part thereof completely immersed in the fuel, another part being out of the fuel and arranged within the chamber to be subject to air currents.

17. In the combination of liquid fuel and

a chamber, means for accelerating evaporation of the fuel by capillary action, said means including a wick having a part thereof completely immersed in the fuel, another part being out of the fuel and disposed within the chamber, and a heater above the fuel and in contact with the exposed part of the wick.

18. In a vaporizer means for increasing the rate of evaporation by drawing a liquid fuel into a chamber by capillary action, said means comprising a wick having a portion constantly covered by a liquid fuel, and a heater for the uncovered portion of the wick, to accelerate evaporation.

19. In a vaporizer means for increasing the rate of evaporation by drawing a liquid fuel into a chamber by capillary action, said means comprising a porous member having a portion constantly immersed in a liquid, the other portion being out of the liquid and exposed in a chamber to present a relatively large surface saturated with the fuel by capillary action with which air currents may contact.

20. A vaporizer for carburetors comprising an elongated porous member having an electric heater at one end adapted to be exposed in a chamber above the liquid fuel, the other end of the porous member being immersed in the liquid fuel whereby the fuel may be drawn to the exposed end by capillary action and vaporized in the chamber.

In witness whereof I have hereunto set my hand this 22nd day of October in the year 1913.
